UNITED STATES PATENT OFFICE.

ROBERT F. WATCHORN, OF MILLBURY, MASSACHUSETTS.

DOBBY.

1,074,670.

Specification of Letters Patent.

Patented Oct. 7, 1913.

Application filed December 5, 1912. Serial No. 735,018.

To all whom it may concern:

Be it known that I, ROBERT F. WATCHORN, a citizen of the United States, residing at Millbury, in the county of Worcester and 5 State of Massachusetts, have invented a new and useful Dobby, of which the following is a specification.

This invention relates to a dobby capable of general application, and in which the 10 harness jacks are moved positively in one direction only, the return movement of the harnesses being accomplished by means of spring connections.

A dobby constructed in accordance with 15 my invention comprises important advantages when used upon any form of work ordinarily produced by a dobby loom, but is particularly adapted to the production of that class of fancy goods which are 20 termed "full-turn lenos." The production of this type of fancy weave upon a dobby of ordinary form, such for instance as that shown in the patent to Crompton, No. 771,462, of Oct. 4, 1904, involves a rearrangement of parts and an addition of auxiliary mechanism. Leno weaving of this 25 description is usually four harness work, the harnesses taken in order from front to back being designated as the "doup harness," 30 the "front standard harness," the "cross-over harness," and the "back standard harness." The operation of the first and last mentioned of these harnesses presents no difficulties, as the harnesses have the usual 35 full-up or full-down motion, and the order in which these motions take place may be readily controlled by the usual pattern chain. The so-called front-standard and cross-over harnesses however, have a pecu- 40 liar motion for the production of which the ordinary dobby is not well adapted. The front-standard harness is maintained in the upper shed at each pick, but must be brought to half-way down or to middle 45 position between each two successive picks. To accomplish this on the ordinary dobby, it is necessary to use two jacks for each harness, and to insert temporary attaching means between the second or auxiliary jack 50 and the harness. With this arrangement, one jack allows the harness to descend under the influence of the usual retracting spring, until it reaches mid-position when the second jack traveling in the opposite direction 55 picks up the harness and raises it again to the upper shed.

The connections necessary to permit two jacks to operate upon a single harness are of more or less delicate construction, and much difficulty is experienced in their operation. The movement of the cross-over harness presents still more serious difficulties. This harness is normally maintained in the lower shed at each pick, but must be raised to mid-position between each two successive picks. 60 This movement cannot be performed by the ordinary harness jacks, as there is no method by which a jack when once started in the upward direction can be stopped until it has performed its full 65 stroke. With the usual dobby, therefore, it is necessary to disconnect the cross-over harness entirely from the usual jack operating mechanism and to provide some form of independent auxiliary mechanism 70 commonly known as a "jumper" to operate the cross-over harness. 75

It is one of the objects of my invention to produce a dobby in which the peculiar motions of the front standard and cross- 80 over harnesses may be secured merely by the proper pinning of the pattern chain, and without the use of auxiliary mechanism or rearrangement of parts.

Another object of my invention is to pro- 85 vide improved means for operating the pattern chain and hook-lifting mechanism.

Further objects of my invention will appear in the following specification.

Reference is to be had to the accompany- 90 ing drawings in which—

Figure 1 is an end elevation of a leno dobby constructed in accordance with this invention; Fig. 2 is a front elevation there- 95 of, and Fig. 3 is a vertical sectional view on the line 3—3 of Fig. 1.

The invention is shown as applied to a dobby provided with jacks 4. The jacks are pivoted on a transverse rod 5 and removably supported thereon. Each one is 100 provided with a curved slot 6 through which slots passes a rod 7 supported in stationary position on the frame to limit their motion for the purpose of lifting the harnesses in the usual way. The means for operating 105 the jacks will now be described.

With each jack is pivotally connected a hook 9 and to it is pivoted a second hook 10. Thus these hooks reciprocate in pairs. The mechanism illustrated herein is intend- 110 ed to be run by a crank or eccentric on the crank-shaft (not shown) of the loom.

This crank is connected with a link 11 which is adjustably connected with an arm 12 having a slot therein for the connection. This arm is fixed on a rock shaft 13 supported by the frame and is thus given a complete up and down reciprocation for each revolution of the crank shaft, and hence for each pick of the shuttle. On the shaft 13 are a pair of arms 14 extending in opposite directions and connected with links 15 and 16, respectively, which are in turn connected with reciprocating knives 17 and 18. Thus the two knives reciprocate alternately and each performs a complete reciprocation for each pick of the shuttle. The knife 17 operates under the set of hooks 9 and the knife 18 operates under the hooks 10. The links 16, as shown in Fig. 2, are pivoted to the arms 14 at a greater distance from the axis than the links 15, and hence the knife 18 receives a greater travel than the knife 17. Each knife has also a certain amount of idle travel or lost motion at the left extreme of its travel, as shown at 18 in Fig. 2, and at 25 17 in Fig. 3, this idle travel being beyond the limit of travel of the hooks 9 and 10 toward the left. The arms 14 are so proportioned that the effective travel of the knife 17 is substantially one half that of the knife 18. In other words, the knife 17 which engages all of the jack hooks 9 at each pick raises them only half way, thus bringing the warp threads controlled thereby to substantially horizontal position, while 30 the knife 18 which engages certain of the hooks 10 as determined by the pattern chain moves those hooks to the extreme right-hand position in Fig. 2, thus raising the warp threads controlled thereby to the extreme upward position. This arrangement possesses certain peculiar advantages in the production of lenos which will be herein-after explained, but it also possesses distinct advantages when applied to any weave 35 in which one or more of the harnesses remains in the lower shed for a succession of two or more picks. On the rock shaft 13 is another arm 20 with which is connected a link 21 operating to oscillate an arm 22 on a short shaft 23 which is provided with a spring-pressed roll 24 adapted to coöperate with a cam wheel 25 on the chain cylinder shaft 26. This shaft is supported on another arm 27 extending from the shaft 23 and the oscillation of the arm 20 causes the chain cylinder 28 to rise and fall at regular intervals. At each reciprocation of the cylinder and while the pins are substantially out of contact with the tumblers, the cylinder is turned one step by any suitable means, such as a ratchet 25^a, (see Fig. 2) coöperating with a hooked pawl mounted upon a stud fixed to the frame of the dobby. The pattern cylinder is thus advanced one step 60 for each vertical reciprocation thereof or

for each pick of the loom, and when so advanced is held from further movement by the spring-pressed roll 24 which coöperates with the cam wheel 25. The rise and fall of this chain cylinder operates tumblers 29 which are pivoted on a rod 30 and operate in grates 31. Each of these tumblers is provided with a wire 32 which operate on the hooks 10. When the cylinder rises the wires 32 corresponding to the pins then at the top of the cylinder drop and thus allow the hooks 10 to drop. 70

This construction is designed to overcome certain objections to the use of the rigidly mounted pattern cylinder heretofore common and disclosed in the patent to Crompton mentioned, in which the pins have a sliding motion relative to the tumblers. When metal pins are used this constant sliding motion results in excessive wear of the tumblers, and when it is sought to avoid this wear by the use of wooden pins, the pins frequently break and cause imperfections in the cloth which continue until the broken pin is detected. In my arrangement the pattern cylinder is turned when the pins are substantially out of contact with the tumblers, and are then moved toward the tumblers in a direct lineal motion so that the wear due to the sliding contact is eliminated. 80

The operation of my device in the production of full-turn lenos will now be explained:—

For the operation of the front standard harness which, as before stated, is normally 100 in the upper shed and is brought half down and returned to upper position between each two successive picks, it is merely necessary to arrange the pattern chain so that the hook 10 connected with said harness shall remain substantially in lowered or operative position. Assuming that the harness is up and the knife 18 is about to commence its travel toward the left in Fig. 3, it will be seen that the harness will be lowered until the hook 9 contacts with the knife 17, which is at this time moving toward the right in Fig. 3 and which will prevent the retracting springs from depressing the harness below the horizontal position of the warp threads controlled thereby. As the knife 18 performs a complete reciprocation and returns to the extreme right position between each two successive picks, it will be evident that if the hook 10 is allowed to remain in lowered position, the knife 18 will again assume control of said hook upon its return travel toward the right and will return the harness to extreme upper position. 110

The operation of the so-called cross-over harness which is normally in the lower shed and is raised to mid-position between each two picks is accomplished by simply maintaining the hook 10 connected therewith in raised position, so that the harness is op- 125 130

erated entirely by the knife 17 through the hook 9. This knife, as before stated, raises all of the harnesses to mid-position between each two picks of the loom, and therefore, 5 communicates precisely the desired motion to the cross-over harness. It will be evident that the raising of all of the harnesses to mid-position will relieve the warp threads in the lower shed of the excessive strain in 10 beating up, which is experienced when certain of the harnesses are maintained in lowered position during the forward beat of the lay.

Although I have illustrated and described 15 one form in which the invention may be made, I am aware of the fact that modifications can be made therein without departing from the scope of the invention as expressed in the claims. Therefore, I do not wish to 20 be limited to the details of construction herein shown and described, but

What I do claim is:—

1. A dobby comprising a set of jacks, a pair of hooks connected to each jack, and a 25 reciprocating knife for moving each hook, each of said knives making a complete reciprocation during each pick of the loom, and one of said knives having an effective travel substantially twice that of the other 30 knife.

2. A dobby comprising a set of jacks, means to move all of said jacks to mid-position at each beat of the lay, and selective means to move certain of said jacks to ex- 35 treme upper position.

3. A loom having in combination harnesses, jacks connected to said harnesses, hooks mounted on said jacks, and a second set of hooks pivotally mounted on said first 40 mentioned hooks, means for moving said first mentioned hooks to raise all of the harnesses to mid-position at each beat of the lay, means for moving the harnesses connected to certain of said second mentioned 45 hooks to extreme upper position, and pattern means for selecting said last mentioned harnesses.

4. In a dobby, a jack, a pair of hooks connected to said jack, and means operable upon 50 said hooks to raise said jack to extreme upper position for successive picks and to permit said jack to be moved to mid-position between such successive picks.

5. In a dobby, a jack, a pair of hooks

connected to said jack, and means operable 55 upon said hooks to raise said jack from extreme lower to mid-position and to permit said jack to return to extreme lower position between two successive picks of the 60 loom.

6. In a dobby, a pair of reciprocating knives, a pattern cylinder, an oscillating shaft, means on said shaft to reciprocate said knives simultaneously in opposite directions, additional means on said shaft to 65 raise and lower said cylinder, an operating arm on said shaft, and a link directly connecting the arm to the crank shaft of the loom, whereby the knives and cylinder each perform a complete cycle of movements at 70 each revolution of the crank shaft.

7. In a dobby, a pattern cylinder, pattern pins mounted thereon, a set of tumblers, and means for both raising and lowering said cylinder between each two successive 75 picks of the loom, said cylinder being rotated step by step when said pins are substantially out of contact with said tumblers.

8. In a dobby for looms, the combination with a set of jacks, of hooks connected with 80 the jacks, additional hooks connected with the first named hooks and movable therewith, two knives, one adapted to coöperate with each set of hooks, and means for simultaneously reciprocating said knives in 85 opposite directions and for returning them to their original positions during each complete beat of the lay.

9. In a loom, a crank shaft in combination with a set of jacks, hooks connected with the 90 jacks, additional hooks connected with the first named hooks and movable therewith, two knives, one adapted to coöperate with each set of hooks, an oscillating shaft having 95 arms projecting therefrom in opposite directions, a link from each arm to one of said knives for operating it, and an additional arm on said oscillating shaft connected by a link to the crank shaft, whereby each knife is given a complete reciprocation for each 100 beat of the lay.

In testimony whereof I have hereunto set my hand, in the presence of two subscribing witnesses.
